UNITED STATES PATENT OFFICE.

JOHN JORDAN AND GEORGE NAYLOR, OF SALT LAKE CITY, UTAH TER.,
ASSIGNORS TO THEMSELVES, A. M. MORTIMER, AND WILLIAM NAYLOR,
OF SAME PLACE.

IMPROVEMENT IN MECHANICAL MOVEMENTS.

Specification forming part of Letters Patent No. 178,062, dated May 30, 1876; application filed April 25, 1876.

To all whom it may concern:

Be it known that we, JOHN JORDAN and GEORGE NAYLOR, of Salt Lake City, Salt Lake county, Territory of Utah, have invented a new and Improved Mechanical Movement, of which the following is a specification:

The figure is a plan view of our improved mechanical movement.

Similar letters of reference indicate corresponding parts.

The object of this invention is to furnish an improved mechanical movement for use upon reapers, mowers, sewing-machines, pumps, hammers, saws, and other machines where a rotary motion is to be converted into a rapid vibratory motion.

The invention consists in the combination of the shaft, the three-armed cam, and one or more notched and pivoted triangular blocks with each other and with their inclosing-case, for converting a rotary into a vibratory motion, as hereinafter fully described.

The case consists of two circular plates, A, attached to a hoop or flange, B, by which they are kept at the proper distance apart. To the center of the plates A is pivoted a shaft, C, to one end of which the power is applied. To the shaft C, within the case A B, is rigidly attached a three-armed cam, D. To the case are pivoted one, two, or three blocks, E, which are made triangular in their general form, and

are pivoted at their angle. The third sides of the blocks E are turned toward the cam D, and are notched in such a way that, as the said cam revolves, each of its arms will strike the first arm of block E, push it back, enter the notch of said block, strike its other arm, and push it forward, so that each block will receive six distinct impulses at each revolution of cam D.

Motion may be communicated from the block E to the object to be vibrated by an arm, F, formed upon, or rigidly attached to, the said block at its pivoted angle, as indicated at the left-hand side of the figure, or by connecting-rods pivoted to the ends of the arms of said blocks, as indicated by the pins G at the right-hand side of the figure.

Having thus described our invention, we claim as new and desire to secure by Letters Patent—

The combination of a shaft, C, the three-armed cam D, and one or more notched and pivoted triangular blocks, E, with each other and with the case A B, for converting a rotary into a vibratory motion, substantially as herein shown and described.

JOHN JORDAN. [L. S.]
